UNITED STATES PATENT OFFICE.

WILLIAM J. PURDY, OF CARBERRY, MANITOBA, CANADA, ASSIGNOR OF TWO-THIRDS TO JOHN PETERS ANDERSON AND ROBERT HENRY D. S. MONTAGU, BOTH OF SAME PLACE.

BUCKET-ELEVATOR FOR FLOURING-MILLS.

SPECIFICATION forming part of Letters Patent No. 415,819, dated November 26, 1889.

Application filed July 31, 1889. Serial No. 319,351. (No models)

To all whom it may concern:

Be it known that I, WILLIAM JETHRO PURDY, of Carberry, in the county of Norfolk, in the Province of Manitoba, in the Dominion 5 of Canada, have invented a certain new and useful Improvement in Bucket-Elevators for Flouring-Mills; and I do hereby declare that the following is a full, clear, and exact description of the same, reference being had to 10 the accompanying drawings.

Figure 1 is a section of a portion of a bucket-elevator, showing my cleaner or brush applied thereto. Fig. 2 is a section of my improved elevator on the line x x , Fig. 1. Figs. 15 3, 4, and 5 are perspective views of detached portions of the brush to show the construction.

My invention has for its objects to remove the accumulation of flour adhering to the 20 trunk or tube of flour-elevators, and thereby prevent flour from being deteriorated by the accumulation loosening after becoming musty and mixing with the flour, and also, by removal of such accumulation, to prevent the 25 tube or trunk from becoming rotten, because of the dampness in the adhesive particles of flour.

My invention consists in securing to the elevator-belt, and between the cups or buckets 30 thereon, one or more brushes which will sweep three sides of the trunk and thereby prevent accumulation of flour adhering to the interior.

A is the endless belt, B the cups or buckets, 35 and C the tube or trunk of the elevator as used in flouring-mills.

D is a brush riveted to the belt, and has frictional contact with three sides of the elevator-tube C to sweep off particles of flour, 40 which, owing to the heat and moisture generated in manufacturing or grinding, cling to the sides of the elevator-trunk, and if not removed become musty, rot the trunk, and injure the flour.

The brush D is preferably composed of a 45 metallic rectangular frame E, having a central opening J, and provided with a flange 2, which is secured to the belt by rivets or bolts F to hold the brush at right angles to the belt, and to said frame E is secured a U- 50 shaped cover-plate G, corresponding to three sides of frame E and placed one over the other.

H H are flexible plates of rubber, cloth, leather, or other suitable material intervening 55 the frame E and cover G and project from the outside edge on three sides, and between said plates H H and projecting therefrom is secured a brushing I, of bristles, steel wire, or other suitable material, by bolts or rivets 60 3, which pass through and compress together the frame E and cover G to hold the plates H H and brushing I interveningly. The brushing I sweeps the finer particles of flour which have adhered to the tube during the 65 operation of the elevator, and the dislodged material passes through the aperture J in the brush and falls into the bucket or cup below.

I claim as my invention—

1. The combination, with the elevator-tube C and endless belt A, having cups or buckets B, of an open-framed brush D, having one side attached to the belt and its bristle or wire ends arranged in frictional contact with 75 three sides of the tube, as set forth.

2. The combination, with the elevator trunk or tube C and endless belt A, having buckets or cups B, of a brush D, provided with a central aperture J and secured to the 80 belt to sweep three sides of the trunk or tube, as set forth.

WILLIAM J. PURDY.
